UNITED STATES PATENT OFFICE.

AMERICUS F. CALLAHAN, OF WINNETKA, ILLINOIS.

BOTTLE STRUCTURE.

937,049.

Specification of Letters Patent. Patented Oct. 19, 1909.

Application filed January 27, 1908. Serial No. 412,740.

To all whom it may concern:

Be it known that I, AMERICUS F. CALLAHAN, a citizen of the United States, residing at Winnetka, in the county of Cook and

5 State of Illinois, have invented a certain new and useful Improvement in Bottle Structures, of which the following is a full, clear, concise, and exact description, reference being had to the accompanying drawings, forming a part of this specification.

10 My invention relates to bottle structures and comprises two separate bottles, one adapted to be inserted within and withdrawn from the other through the opening in the latter, and a plug stopper sufficiently large at its top to plug the opening in the outer bottle and sufficiently small at its bottom to plug the opening in the inner bottle, said plug stopper being adapted to carry

15 with it the inner bottle when withdrawn from the opening in the outer bottle, the smaller end of the plug stopper being removable from the opening in the inner bottle after the larger end of the plug stopper

20 has been removed from the opening in the outer bottle.

25 I will explain my invention more fully by reference to the accompanying drawing, showing the preferred embodiment thereof,

30 in which—

Figure 1 is a sectional elevation of a bottle made in accordance with one embodiment of the invention. Fig. 2 is a view of the inner compartment before its insertion or after its withdrawal from the outer compartment. Fig. 3 is a view showing the outer compartment. Fig. 4 is a view of the stopper unassociated with either compartment.

35 40 Like parts are indicated by similar characters of reference throughout the different figures.

45 As hitherto stated, the bottle compartments are preferably so related that one is inclosed by another, the outer bottle compartment *a* and the inner bottle compartment *b* having neck or outlet portions *c d* which are adapted to receive a stopper *e* serving to seal both bottle openings. The

50 stopper is desirably in the form of a cork whose upper portion is enlarged to fit the neck portion *c* of the outer compartment *a*,

the lower and smaller portion of the cork being adapted to fit the discharge opening of the inner bottle compartment *b*.

55

The inner bottle compartment *b* is first corked or sealed by the stopper *e*, as indicated in Fig. 2, whereafter it is passed into the interior of the bottle compartment *a* to an extent that will permit the larger portion of the cork or stopper to seal the outer bottle opening, it being understood, of course, that in order that the bottle structure may be of service, the inner compartment is first filled with the material it is to contain and the outer compartment is partially filled with the material it is to contain, the stopper taking part in the support of the inner compartment as well as sealing both compartments.

60

65 It is obvious that the bottle of my invention is capable of holding liquids or solids and that in either case the contents of the bottle compartments act in coöperation with the common stopper to support the inner 70 bottle compartment in place, whereby the walls of the inner bottle compartment may be made quite thin, if desired.

70

75 The bottle structure of my invention is designed for the purpose of normally maintaining a plurality of substances in collocation without their intermixture and whereby when the substances are to be intermixed such intermixture may be readily effected by the withdrawal of the common stopper from 80 the outer bottle compartment to open that compartment and take with it the inner bottle compartment and thereafter the withdrawal of the stopper from the inner bottle compartment, whereupon the two normally 85 separated substances contained in the bottle compartments may be intermixed.

90

95 Having thus described my invention, I claim as new and desire to secure by Letters Patent:—

A bottle structure comprising two separable bottles, one adapted to be inserted within and withdrawn from the other through the opening in the latter, and a plug stopper sufficiently large at its top to plug 100 the opening in the outer bottle and sufficiently small at its bottom to plug the opening in the inner bottle, said plug stopper being adapted to carry with it the inner

bottle when withdrawn from the opening in the outer bottle, the smaller end of the plug stopper being removable from the opening in the inner bottle after the larger end of the plug stopper has been removed from the opening in the outer bottle.

In witness whereof, I hereunto subscribe

my name this 25th day of January, A. D., 1908.

AMERICUS F. CALLAHAN.
